UNITED STATES PATENT OFFICE.

RALPH S. MEGATHLIN, OF SOMERVILLE, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

1,386,642.

Specification of Letters Patent.

Patented Aug. 9, 1921.

Application filed August 1, 1919. Serial No. 314,711.

To all whom it may concern:

Be it known that I, RALPH S. MEGATHLIN, a citizen of the United States, residing at Somerville, in the county of Middlesex and

5 State of Massachusetts, have invented certain Improvements in Heel-Building Machines, of which the following description, in connection with the accompanying drawings, is a specification, like reference characters on the drawings indicating like parts in the several figures.

10 This invention relates to machines for building heels for boots and shoes, and more particularly to means for assembling 15 a number of lifts or blanks and securing them in assembled relation.

In accordance with a practice heretofore followed, it has been customary to manually assemble a number of blanks or heel lifts, 20 one on top of another in a mold, whose interior contour corresponded with the contour desired for the pile of lifts, and then secure the lifts together either by an adhesive or fastening, or both. This system, however, 25 has been found objectionable on account of the large number of molds required for the great variety in the form of heels desired, and because the glue or adhesive with which the adjacent surfaces of the blanks or lifts 30 are coated, soon gums up the mold, and much loss of time results in maintaining the molds in proper working condition.

Another system has suggested an arrangement of a number of piles of small 35 plates about a central forming space, and securing the plates of each pile together when they have been placed with their edges in a desired overlapping condition generally conforming with the desired pitch of the 40 heel. In forming the pile of lifts according to this system, the operative or machine attendant feels the gage plates about the forming space with one hand and with the other selects the lift or lifts which, to the 45 sense of touch, seem of the proper thickness to bring the heel to the desired height. The pile of lifts thus formed is then lined up against a breast gage or plate at one side of the central forming space, about the contour 50 portions of which the piles of gage plates are secured in fixed positions. Much difficulty is encountered where the heel form is thus composed of relatively adjustable

plates, because the heel lifts are not always of the same thickness as the plates, and consequently, as the lifts are stacked in the form they are not always accurately alined. Moreover, since the plates are separate and independent of each other, considerable skill is required to pile them in the desired 60 relation, especially when they become more or less covered with the glue or adhesive used to hold the surfaces of the lifts in close contact. In this, as in the older method, the uniformity of product and accuracy of 65 the pile of lifts to respond to the desired character of heel, have depended upon the skill and care of the operative or machine attendant, and the amount of work turned out in any predetermined period of time has 70 been necessarily limited by the manual operations required in building the heels.

When a pile of assembled lifts is completed, it is desirable that the breast edge portions of the pile of lifts or blanks shall 75 be in substantially the same plane and that the contour portions of the lifts or blanks shall be related in substantial conformity with the desired pitch of the heel.

An important feature of the present invention, therefore, consists in a series of heel plates extending heightwise of a pile of lifts assembled on a lift support and adjustable to different inclinations with respect to the surface of the support on which the lifts 80 are assembled and to different positions around the contour of the pile of lifts. Since the heel plate is continuous heightwise of the heel, and is inclined in accordance with the pitch desired for the pile of lifts, 85 it follows that the several strata of lifts throughout the height of the heel will conform substantially to the pitch desired when the heel plate is brought in contact with the contour edges of the lifts.

When the pile of lifts of appropriate thickness have been assembled on the lift support, it is desirable that they be lined up against the breast gage to bring the breast edge portions of the lifts in the same 100 plane and cause the contour edge portions of the lifts to partake of the inclined relation defined by the heel plates. Another important feature of the invention, therefore, consists of mounting the heel plates 105 about the forming space in groups upon

carriers arranged for movement in directions diagonally converging toward the breast gage or plate.

In carrying this feature of the invention 5 into practical effect, the series of heel plates adjustable as to inclination relative to the lift support, are assembled on clamping blocks which are simultaneously movable in diagonally converging directions toward the 10 heel breast plate or gage.

Another important feature of the invention consists of mounting the heel plates for 15 adjustment on the clamping blocks in a curved path extending about the central forming space. This feature of the invention may be variously contrived, but in the present instance, several clamping plates, 20 extending heightwise of the pile of lifts on the lift support, are adjustable in a curvi-linear path on the clamping blocks and are adapted to be secured in adjusted position on their respective blocks.

Other features and novel combinations of 25 parts will hereinafter be described, and then the true scope of the invention will be defined by the claims.

In the drawings:

Figure 1 represents in perspective view, 30 sufficient portions of a heel building machine with the present invention embodied therein, to make clear the construction and mode of operation of the invention and associated parts;

Fig. 2 is an enlarged view showing the 35 parts in separated relation and some of the elements broken away.

The invention is herein illustrated for 40 convenience as applied to a manually operated heel building machine, but may be advantageously employed in a power operated machine, many types of which are well known in the art. The frame of the machine may be of any desired construction 45 and character for supporting the operating parts, and in the present instance comprises under supporting members 1 on which is mounted a bed or supporting top 2. This construction lends itself particularly to a manually operated heel building machine, 50 and in case the invention is used in a power operated machine, the supporting frame will be correspondingly changed to afford proper sustaining means for the operating parts.

Mounted on the machine frame is a carrier or support 3 which may be sustained 55 upon the support by any suitable means. In the present instance the machine frame has rising therefrom, at each side thereof, the brackets 4 through which extend the 60 adjusting screws 5 having the thumb piece 6 by which the screws may be manually adjusted. The end portion of the adjusting screws 5 is tapered or pointed, as at 7, to engage the carrier 3. In the present instance the adjusting screws 5 engage the

side of the carrier 3 and may be withdrawn from engagement therewith by reverse rotation of the adjusting screws to permit the carrier 3 to be reversed end for end as and for a purpose that will later appear. 70

The carrier 3 has connected thereto the lift support and heel clamping blocks carrying the heel plates. The lift support may be variously contrived, but in the present instance is formed by a block 8 secured to 75 the carrier 3 and adjustably connected thereto is a breast gage or plate 9 having a slot 10 through which extends a securing bolt 11, the construction being such that the breast gage or plate 9 may be adjusted relative to the lift support 8 to present an 80 abutment or gage for the breast edge portions of the pile of lifts assembled on the lift support.

Mounted upon the carrier 3 for movement 85 relatively thereto, in a direction diagonally converging toward the breast gage or plate 9, are the heel clamping blocks 12 carrying the heel plates. The described movement of the heel clamping blocks 12 may be imparted 90 by variously contrived forms of mechanisms, but in the present instance of the invention the heel clamping blocks 12 have extending downwardly therefrom means for engaging inclined slots formed in the carrier 3. The 95 carrier 3, see Fig. 2, has formed upon its under surface, the inclined guides 13 which converge inwardly toward the heel breast gage or plate 9. The carrier 3 is also provided with the converging slots 14 through 100 which extends a guide member 15 projecting from each of the heel clamping blocks. The guide member 15 engages between the inclined guides 13, 13, secured to the under surface of the carrier 3, the construction 105 being such that movement of the guide member 15 in the guide-ways afforded by the inclined guides 13, 13, will cause the heel clamping block to which the guide member 110 is secured, to move diagonally relative to the gaging face of the heel breast gage or plate 9.

Extending downwardly from each of the 115 guide members 15, is a pin 16 carrying a roll 17.

The machine top or bed 2 is provided with transversely arranged slots 18, 18, in which are guided the actuating members 19, 19, carrying rolls or pins 20 upon their upper portions above the top surface of the 120 bed 2. The guiding members 19 are pivoted to the machine frame at 21, and their lower extending ends 22 are connected by toggles 23 jointed together at 24 and connected to an operating member 25, which, in the present instance, is treadle actuated.

When the carrier 3 is in operative position, as indicated in Fig. 1, the rolls 17 extending from the heel clamping blocks are positioned in front of the rolls 20 carried by 130

the actuating members 19, the construction being such that should the upper ends of the actuating members 19 be moved toward each other, the rolls 20 acting upon the rolls 17, 5 will cause the heel clamping blocks 12 to be moved in a direction diagonally converging toward the breast gage or plate 9. The rolls 20 on the actuating members 19 are sufficiently long to maintain contact with the 10 rolls 17 throughout the sliding movement of the heel clamping blocks.

In order to move the heel clamping blocks in a direction diagonally away from each other and from the breast gage or plate 9, 15 any convenient means may be provided, a good form of such means being shown in Fig. 2. In this instance the means comprises springs 26, one end of which is connected at 27 to each guide member 15, and 20 the other end of which is secured at 28 to a fixed point on the carrier 3, the construction being such that when the heel clamping blocks 12 have been moved diagonally toward the heel breast or gage 9, and then 25 released, the springs 26 will return the respective heel clamping blocks to their normal outward position.

Each of the heel clamping blocks carries 30 a series of heel plates which are adjustable to different inclinations relative to the surface of the lift support. In the present instance each of the heel clamping blocks is provided with a groove or slot 29, Fig. 1, in which a series of blocks 30 are mounted. 35 The blocks 30 afford one convenient means for carrying the heel plates and are adjustable in the grooves or slots 29, which are preferably curved, as indicated in Fig. 1. The curvature of the slots 29 approximately 40 corresponds with the general curve or contour of the pile of lifts arranged upon the lift support 8.

Extending upwardly from each of the blocks 30 is a threaded pin 31 which passes 45 through slots 32 and 33 formed in the adjusting plates 34, 35, respectively. Threaded to each of the stems 31 above the adjusting plate 34, is a winged nut 36 adapted to clamp the adjusting plate 34 in adjusted 50 position on the heel clamping block 12. The upper end portion of the stems 31 are enlarged, as at 37, and below the adjusting plate 35 each stem is provided with a wing nut 38, the construction being such that by 55 manipulation of the nut 38 the adjusting plate 35 may be held in adjusted position. Extending between the inner end portions of each of the adjusting plates 34 and 35 is a heel plate 39 preferably hinged as at 40, to 60 the upper and lower adjusting plates, the construction being such that by manipulation of the winged nuts 36 and 38, the adjusting plates 34 and 35 may be moved bodily lengthwise upon their supporting heel 65 clamping blocks; and by manipulation of

either of the winged nuts 36 or 38, the inclination of the heel plate 39 carried between them may be adjusted relative to the lift support 8.

Various means may be suggested for adjusting the inclination of the heel plates 39, but the described construction presents a convenient and simple form of means to this end, whereby the inclination of the heel plates relative to the lift support may be 75 adjusted in accordance with the desired pitch of the pile of lifts assembled on the support.

From the construction described it will be apparent that when a pile of lifts or blanks 80 has been assembled on the lift support, and the heel clamping blocks are moved in a diagonally converging direction toward the heel breast gage or plate 9, that the series of lifts will be lined up against the breast 85 gage or plate 9 with their contour edges in contact with the inclined surfaces of the heel plates 39, which thereby determine the inclination or pitch of the heel.

The heel clamping blocks 12 may be variously formed and of any desired number. Two such heel clamping blocks are shown 90 and their contiguous ends 41 are shaped to permit the heel clamping blocks to be moved in the diagonal direction described.

It is usual in building heels to apply an adhesive to the surface of each of the lifts and as a convenient means to this end a roller 42 is mounted in a glue or adhesive tank 43 so that the machine attendant may 100 conveniently apply an adhesive to the surfaces of the heel lifts.

Some machine attendants or operatives can work better when the breast gage or plate 9 is at the front of the machine adjacent to the attendant, while others can operate the machine with more facility when the breast gage or plate 9 is at the rear. To accommodate each of the operatives or attendants, the carrier 3, as hereinbefore described, is mounted between the adjusting screws 5 in a manner to permit the carrier 3 to be detached from the screws 5 and turned horizontally 180°. Thus a suitable and effective means is provided to permit the attendant to adjust the carrier with the breast gage or plate 9 either at the front or at the rear of the machine as his or her preference may dictate.

As a convenient means for the ready assembling of lifts the carrier 3 may be mounted upon the machine frame for slight tilting movement, so that the attendant may tilt the carrier 3 either forwardly, as indicated in Fig. 1, or backwardly, as may best suit him 110 or her.

The carrier 3 may be provided with openings 44 through which any dirt, scraps, or other foreign matter may pass.

Having described my invention what I 130

claim as new and desire to secure by Letters Patent of the United States is:—

1. In a heel building machine, the combination of a support for a pile of heel lifts, 5 heel plates arranged about a central forming space and extending in a direction heightwise of a pile of lifts on said support, means for adjusting the inclination of the plates relative to the surface of the support, 10 and means for adjusting the heel plates to different positions about the forming space.

2. In a heel building machine, the combination of a support for a pile of heel lifts, a heel plate extending from a point adjacent 15 the surface of the support to the top of a pile of lifts on said support, means for adjusting the heel plate about the pile of lifts to engage the edges of the lifts at different positions about the pile of lifts, 20 and means for adjusting the inclination of the plate relative to the surface of the support in accordance with the desired pitch of the heel.

3. In a heel building machine, the combination 25 of a lift support, a breast gage, heel clamping blocks each carrying a series of heel clamps which engage the edges of a pile of lifts on the lift support, and means for moving the heel clamping blocks in 30 directions diagonal to the heel breast gage to move the lifts into contact therewith and aline the edges of the lifts.

4. In a heel building machine, the combination 35 of a lift support, a breast gage, two heel clamping blocks each carrying a series of heel clamps, and means for moving the heel clamping blocks in directions diagonally converging toward the breast gage to aline the lifts against the breast gage.

40 5. In a heel building machine, the combination of a lift support, a breast gage, two heel clamping blocks each carrying a series of heel clamps, means for adjusting the individual clamps to different positions 45 on the clamping blocks, and means for moving the heel clamping blocks in directions diagonally converging toward the breast gage to aline the lifts against the breast gage.

50 6. In a heel building machine, the combination of a support for a pile of heel lifts, a breast gage, heel clamping blocks arranged about a central forming space and carrying heel clamps, means for adjusting 55 the clamps on the clamping blocks to different positions about the forming space, and means for simultaneously moving the clamping blocks in directions diagonally converging toward the breast gage to move 60 a pile of lifts on said support and aline them against the breast gage.

7. In a heel building machine, the com-

bination of a support for a pile of heel lifts, a breast gage, heel clamping blocks arranged about a central forming space and carrying heel clamps, means for adjusting the clamps on the clamping blocks in a curved path to different positions about the forming space, and means for simultaneously moving the clamping blocks in directions, diagonally converging toward the breast gage to move a pile of lifts on said support and aline them against the breast gage.

8. In a heel building machine, the combination of a lift support, a breast gage, heel clamping blocks arranged about the lift support and each provided with a plurality of heel plates that are adjustable to different inclinations relative to the surface of the lift support, and means for moving the clamping blocks in diagonal directions toward the breast gage to aline a pile of lifts against the breast gage with the contour edges of the lifts relatively positioned in the line of pitch.

9. In a heel building machine, the combination of a lift support, a breast gage, heel clamping blocks arranged about the lift support and provided with a plurality of heel plates that are adjustable to different inclinations relative to the surface of the lift support, means for adjusting the heel plates to different locations about the lift support, and means for moving the clamping blocks in diagonal directions toward the breast gage to aline a pile of lifts against the breast gage with the contour edges of the lifts relatively positioned in the line of pitch.

10. In a heel building machine, the combination of a lift support, a breast gage, and heel clamps for lining up a pile of lifts against the breast gage, a carrier by which said lift support, breast gage, and heel clamps are carried, a frame and connections between the frame and carrier permitting the latter to be reversed in position to present the breast gage either to the front or rear of the machine.

11. In a heel building machine, the combination of a lift support, a breast gage, and heel clamps for lining up a pile of lifts against the breast gage, a carrier by which said lift support, breast gage and heel clamps are carried, a frame and connections between the frame and carrier for holding the carrier in an inclined position and permitting it to be reversed to present the breast gage either to the front or rear of the machine.

In testimony whereof I have signed my name to this specification.

RALPH S. MEGATHLIN.
